Primary Examiner—Celia Murphy(74) *Attorney, Agent, or Firm*—Burns Doane Swecker & Mathis, LLP(57) **CLAIM**

The ornamental design for a trail shoe sole, as shown and described.

DESCRIPTION

FIG. 1 is a perspective view looking downward at the front left corner of a left trail shoe sole showing my new design; FIG. 2 is a perspective view looking downward at the left rear corner of the left trail shoe sole in an inverted position; FIG. 3 is a front elevational view thereof; FIG. 4 is a right side elevational view thereof; FIG. 5 is a rear elevational view thereof; FIG. 6 is a left side elevational view thereof; and, FIG. 7 is a bottom plan view thereof. The broken lines showing a shoe upper in FIGS. 1-6 illustrate the environment in which the design resides; the broken lines forming no part of the claim.
